(12) **United States Design Patent** (10) **Patent No.:** **US D1,062,647 S**
(45) **Date of Patent:** **** Feb. 18, 2025**

(54) **CONNECTOR**

(71) Applicant: **SCAN2CAD INC.**, St. Petersburg, FL (US)

(72) Inventor: **Hechuan Xu**, Shanghai (CN)

(73) Assignee: **SCAN2CAD INC.**, St. Petersburg, FL (US)

(**) Term: **15 Years**

(21) Appl. No.: **29/967,558**

(22) Filed: **Oct. 10, 2024**

Related U.S. Application Data

(63) Continuation of application No. 29/948,727, filed on Jun. 22, 2024, now Pat. No. Des. 1,053,826, which is a continuation of application No. 29/923,726, filed on Jan. 1, 2024, now Pat. No. Des. 1,035,585.
